W. S. RAWSON.

SASH FASTENER.

APPLICATION FILED APR. 30, 1914.

1,151,715.

Patented Aug. 31, 1915.

UNITED STATES PATENT OFFICE.

WILLIAM S. RAWSON, OF EAST ORANGE, NEW JERSEY.

SASH-FASTENER.

1,151,715.

Specification of Letters Patent. Patented Aug. 31, 1915.

Application filed April 30, 1914. Serial No. 825,410.

To all whom it may concern:

Be it known that I, WILLIAM S. RAWSON, a citizen of the United States, and a resident of East Orange, county of Essex, and State 5 of New Jersey, have invented certain new and useful Improvements in Sash-Fasteners, of which the following is a specification.

This invention relates to an improved window and is adapted for use in windows 10 which have a sash that is adapted to be lowered into a well when opened and raised when closed, this type of window being particularly desirable in carriages, automobiles and the like.

15 The invention relates particularly to an inconspicuous means for raising and lowering the sash, the said means being adapted to hang within the well, when it is not being actually used to slide the window, whether 20 the window is open or closed.

The invention is further designed to provide means for automatically holding the sash at various heights when the means for raising and lowering the sash is not so employed. The automatic holding device or 25 latch is operative as a support when the lifting means is inoperative, the latch for holding the sash also acting to suspend the sash from the lifting means and thereby release 30 the latch from the element which supports it when the height at which the sash is held is to be changed.

Another feature of the invention is the 35 latch by means of which the sash is raised, lowered or held in place, the latch being simple and easy of operation, its simplicity making the successful operation of it assured.

The invention is also designed to provide 40 a latch constructed to engage a supporting strip, such as a rack, chain or the like, the latch when in operative connection with the strip holding the sash against downward movement and so transmitting the weight of 45 the sash to the supporting strip so that the strip is not forced in a transverse direction so that the panels or other parts of the side walls of the well are not forced outward by the strain. The latch is constructed so that 50 it is operated easily, being forced to open position by the lifting strap or string and the weight of the sash having a tendency to move upward and downward respectively 55 and swing the latch from its engagement with the supporting strip.

A further improvement present in this construction is the handle or grip of the strap, which grip is made to lie close against the glass of the sash and against the top edge of the well so that it is inconspicuous, and 60 is also constructed to provide for its easy grasping by the person who desires to operate the window.

The invention is illustrated in the accompanying drawing in which similar reference 65 numerals indicate corresponding parts in the several views, the construction showing an embodiment of the invention, this embodiment, however, being subject to alteration as to the construction of the parts and 70 also their relative positions without departing from the scope of the invention.

In said drawings Figure 1 is a face view of a window with the lower panel removed to show the inside of the well, the window 75 being broken away at the right side, and Fig. 2 is a side view of Fig. 1, those parts that are broken away in Fig. 1 being shown in section in Fig. 2. Fig. 3 is a front view of the latch on a larger scale. Fig. 4 is a 80 section on line 4, 4, in Fig. 3. Fig. 5 is a top view of the swinging portion of the latch. Fig. 6 is a detail showing a modified form of latch.

In the embodiment of the invention illustrated in the drawing the window consists of a frame 10 which is illustrated as of the usual form and dimensions as employed in doors and windows of automobiles, carriages and the like vehicles, although it will 90 be understood that the invention is adapted to be used in any situation where it is applicable. The frame as shown comprises a top rail 11, side rails 12, one of which is shown, and the bottom rail 13, the lower 95 portion of the frame forming a well, since the side panels 14 and the side strips 15 and 16 inclose this portion of the frame. This structure, of course, is subject to such changes as are necessary for ornamentation 100 which may be necessary in view of the situation of the frame. Sliding in the frame is a sash, and the sash can be of any type, either the ordinary sash inclosing a pane of glass or the like, or it may be as is illustrated in the drawing which illustrates the sash consisting of a glass pane 17 along the bottom edge of which is a strip 18, this structure being called the sash in this specification for the purpose of identification. 110

The sash is guided in its sliding movement, such direction of the path of travel of the sash being provided for within the well by guide-ways 19 on the side frames 12, and when the sash passes upward so as to project into the opening formed in the upper part of the frame, above the side strips 15 and 16, it is directed by suitable guides 20, these being usually pivoted near their top edges as at 21 so that when the sash is up to its closed position, it can be held in such position by means of a hooked portion 22 on the sash strip 18, the hook 22 resting on a rib or rail 23. This manner of supporting the window at its top point is common in windows of this kind, and in the coach and carriage-makers' trade it is known as having the sash "jump the fence," since the pivotal arrangement of the guides 20 allows the bottom edge of the guides to be swung toward the rib 23 and the sash is permitted to have an excess movement upward so as to permit its being jumped over the rail 23. It will be understood, however, that other means may be employed for holding the sash in its closed position. In windows of this kind the sash is lifted from the bottom, and this has been done by a device known in the trade as a "string," this usually consisting of a strap made of leather or canvas or other suitable material, the strap being secured to the bottom of the sash in the old type, and consequently hanging over on the inside of the door when the sash is closed.

In my construction the strap drops down within the well except for its handle at the top and irrespective of the height at which the window is held. In the old type of sliding window the sash is held at an intermediate point by a button-hole in the strap being passed over a stud or button on the inside of the door, or by an equivalent fastening, all this however providing for the end of the strap hanging over on the inside of the door, and in addition to its being in the way, it does not make a good appearance.

In the construction shown I manipulate the sash by means of a strap 24 which has a handle 25 on its top end, the preferred form of handle being described hereinafter, but any suitable handle can be employed so long as it limits the movement of the strap in the well. The strap is normally suspended in the well and is freely slideable therein, being limited, however, in its upward movement relative to the sash by a suitable stop. This stop is shown in the form illustrated as a metallic or similar bar 26 projecting from the sides of the strap toward its bottom end, and being adapted to act as a limit for the upward movement of the strap relative to the sash, this being usually provided for by passing the strap

through a slot 27 in the plate 28 which is fastened to the sash. It will thus be seen that when the strap is pulled up until the stop 26 engages the plate 28, and then is further pulled upward, the sash will be pulled upward with it, and it will also be noted that when the sash is held at any height by means other than the strap, the strap is free to retreat either by gravity or any other force and automatically assume a position suspended within the well, as shown in Figs. 1 and 2. In this manner the strap, except when it is being actually employed in controlling the sliding of the sash, is out of sight except for its handle, and the appearance of the door or other form of frame is not marred by the presence of an overhanging end and the strip is not in the way.

In conjunction with the strap I have devised means for holding the sash at various points in its path of travel, and I prefer to form this holding means in the form of a latch which is operated to engage a suitable support and is also operated to release the sash from the support, but I prefer to combine the strap and the latch so that when the strap supports the sash, the latch is released and vice versa. When the strap is not supporting the sash the latch is permitted to become operative against the support and the strap is free to retreat within the well. The preferred form of latch is illustrated in Figs. 1, 2, 3, 4 and 5 of the drawing, the latching means comprising a latch 29 having the operating plate 28 projecting from the front of it, the latch being pivoted to the lower part of the sash, this being usually done by means of knuckles 31 swinging on a pintle 32 which also passes through the knuckles 33 of a plate 34 fastened to the bottom part of the sash. The plate 34 is bent on its front side into a stop 35 which limits the upward swing of the latch-plate toward the sash on the side of the support. The latch, on its projecting end, is provided with means for engaging a supporting strip, the supporting strip being in the form of a rack or chain, or other similar structure, the preferred form, however, being shown as a rack 36 having the teeth 37 which are so disposed that they form recesses 38 between them, these recesses being adapted to receive a short bar 39 on the end of the latch, the bar forming part of the latch and being preferably provided with a covering 40 which may be of rubber or the like to prevent the clicking which is the result if a metallic latch were passed over the teeth 37.

When the pane 17, or any other form of sash, rests on the latch, the latch-plate 29 is forced up against the stop 35 and supports the sash on the rack by means of its bar 39, the parts being so disposed that the latch-

plate 29 is approximately horizontal so that the strain on the recesses 38 is downward and not sidewise, and there is no tendency of the weight of the sash pushing the rack 26 outward and forcing it against the paneling or any other ornamental covering of the well. In other words, the strain on the supporting strip, such as the rack, is longitudinal along said strip. The releasing plate 28 is provided with a slot 27 through which, as previously described, the strap 24 is adapted to freely slide.

When the sash is at its bottom point or is as far down in the well as it will go, it usually rests on a block 41 which is arranged at the required height and acts as a cushion to support the sash at its lowest point and to also eliminate any noise of contact when the sash is lowered onto the block 41. When the sash is at its lowest point it can be raised in two ways. First, it can be grasped at its top edge and pulled upward as high as desired, the upward movement of the sash not affecting the strap, since the strap 25 slides freely in the slot 27, but the latch passes up over the teeth 37, this passage being substantially noiseless on account of the soft covering 40 of the latch bar 39. When the sash is at the required height it is prevented from descending by reason of the latch being forced against the supporting strip by the spring 42 or any other suitable means for normally forcing the latch in contact with the supporting strip. The other manner of raising the sash is by pulling on the handle 25 which pulls the strap 24 upward, the stop 26 engages the bottom side of the plate 28 which forms a releasing plate, and the strap thus overcomes the pressure of the spring 42 and swings the latch up to the position shown in dotted outline in Fig. 4, thus releasing the latch from its contact with the supporting strip, and the sash can be freely slid to any point up or down by means of the strap. When the sash is to be secured at any height it is either supported by one hand while the strap is released and allowed to fall within the well, after which any release of the sash 50 will force its latch to support it, or the strap can be given a jerk when the sash is at the required height. This upward jerk serves to permit the sash to force the latch in engagement with the strip at the instant following the jerk when the release of the strap from the sash gives the spring 42 a momentary chance to swing the latch into engagement with the supporting strip. Whenever the sash is in the desired place it is understood that the strap 24 can retreat and assume its normal position illustrated in Fig. 1. The handle at the top end of the strap is usually arranged to serve as a stop to limit the descent of the strap, and the preferred form of handle is in the form of a

cylindrical grip 25 which is thick enough to prevent its passing between the glass of the window and the top edge of the well so that it is always in position to be grasped. This form of handle is not conspicuous and is usually provided with soft bands 51, such as rubber or felt, so as to prevent any rattling when used on a vehicle.

In Fig. 6 I illustrate a modified form of latch which is constructed to engage opposite sides of the supporting strip. The device as shown is secured to the bottom rail 18 of the sash and consists of pivoted teeth 51 normally pressed inward by suitable springs 52 so that these teeth normally engage suitable recesses 53 in the supporting strip 54. In order to release the latch I provide the teeth with levers 55 having studs 56 on them, the studs 56 being in the path of the stops 26 of the strap 24. Suitable studs 57 are disposed so as to limit the swing of the levers 55 and engage them so that the sash can be lifted by the stops 26 engaging the studs 56 on the levers 55.

Having thus described my invention, I claim:

1. A device for fastening a sliding sash comprising a supporting strip, a sash sliding adjacent to the strip, a latch adapted to normally engage the strip to support the sash thereon, and a strap to engage the latch to release it and to support the sash.

2. A device for fastening a sliding sash comprising a supporting strip, a sash sliding adjacent to the strip, a latch adapted to normally engage the strip to support the sash thereon, a strap to engage the latch to release it and to support the sash, the strap having a sliding connection with the latch, and means for limiting the upward movement of the strap in the latch.

3. A device for fastening a sliding sash comprising a supporting strip, a sliding sash, a latch normally acting to engage the strip whereby it supports the sash, and manually operated means for lifting the latch and thereby disconnecting it from the strip, whereby the latch supports the sash and depends from said means.

4. A device for fastening a sliding sash comprising the sash, a support, a latch on the sash, a strap connected to the latch, the latch being disposed so that it alternately engages the strap and the support whereby it is supported by first one and then the other.

5. The combination of a frame having a well, a sash adapted to slide into the well, with a sash supporting means in the well, a latch on the sash and in a position to engage the support, and a manually operated means extending to the outside of the well, said means being disposed so that it can operate the latch to release it from the support and suspend the sash on said means.

6. The combination of a frame having a well, a supporting means in the well, a sash arranged to slide in the well, a latch on the sash and adapted to engage the said means 5 to support the sash, and means extending to the outside of the well and adapted to lift the sash by its latch whereby the latch is released from the supporting means.
7. The combination of a frame having a well, a supporting means in the well, a sash arranged to slide in the well, a latch on the sash and adapted to engage the said means to support the sash, and a strap in the well and having means on it for lifting the latch 15 to support the sash and release the latch from the supporting means.
8. The combination of a frame having a well, a supporting means in the well, a sash arranged to slide in the well, a latch on the sash and adapted to engage the said means to support the sash, a strap in the well and having means on it for lifting the latch to support the sash and release the latch from the supporting means, the strap being limited 25 in its free upward movement by engaging the latch, and a handle on the top end of the strap and engaging the top of the well to limit the downward movement of the strap.
9. The combination of a frame having a well therein, a sash sliding in the well, with a strap sliding freely in the well, a slotted plate on the sash through which the strap freely slides, and a stop on the strap for engaging the plate to lift the sash by the strap. 35
10. The combination of a frame having a well therein, a sash sliding in the well, with a strap sliding freely in the well, a slotted plate through which the strap slides, a stop on the strap for engaging the plate to lift 40 the sash by the strap, and an enlargement on the strap to limit the downward movement of the strap when the enlargement engages the top of the well.
11. A window comprising a frame with a well at its lower portion, a sash adapted to slide in and out of the well, a strap sliding freely in the well and normally hanging in the well, means for holding the strap suspended in the well, a stop on the strap, a 45 slotted plate on the sash above the stop, the strap passing through the slot in the plate, and means connected to the plate, said means operating to hold the sash at various points in the well and being inoperative when the sash is suspended, by its plate, on the strap. 55
12. A window comprising a frame with a well at its lower portion, a sash adapted to slide in and out of the well, a strap sliding freely in the well and in its relation to the sash and normally hanging in the well, means on the sash for guiding the strap in 60 its sliding movement, and a stop on the strap to engage the guiding means for limiting the upward movement of the strap relative 65 to the sash.
13. A window comprising a frame having a well therein, a sash sliding in and out of the well, a supporting strip in the well, a latch normally engaging the strip to support the sash at various points, a releasing means 70 on the latch, a strap sliding freely in the well, and a stop on the strap, the releasing means being in the upward path of travel of the stop whereby their engagement releases the latch and supports the sash on the strap. 75
14. A window comprising a frame having a well, therein, a sash sliding vertically in and out of the well, a supporting strip in the well, a latch pivoted to the sash, a stop for limiting the upward swinging of the 80 latch, the supporting strip having means for engaging the latch at various points, means for normally swinging the latch to the position in which it engages the supporting strip, and manually operated lifting means 85 sustained in the well and extending to the exterior thereof, said lifting means being freely slid able in the well and in relation to the sash, releasing means on the sash operatively connected with the latch, and a stop 90 on the lifting means to engage the releasing means on the latch to limit the upward movement of the lifting means relative to the sash whereby the sash is supported on the lifting means and is released from the 95 supporting strip.
15. A window comprising a frame having a well therein, a sash slid able in the well, a supporting strip in the well, a latch pivoted to the sash at the bottom there ¹, the latch 100 projecting on one side of the sash to engage the supporting strip, means for limiting the upward swinging of the latch on the sash whereby the sash can be supported by the latch when it engages the supporting strip, a releasing portion on the latch projecting from the side of the sash opposite the supporting strip, a strap sliding freely through the releasing means, a handle on the top of the strap by means of which it is limited in 110 its movement within the well, and a stop on the strap for engaging the releasing means to limit the upward movement of the strap relative to the sash. 105
16. In a sash adjusting device, a well in 115 which the sash is adapted to slide vertically, a sash sliding in the well, a rack in said well, the rack having upwardly inclined teeth, a latch pivoted to the bottom of the sash, a spring to normally force the latch to an approximately horizontal position, means on the latch for engaging any tooth of the rack whereby the sash can be supported at various heights, means on the sash for limiting the upward movement of the engaging portion, a slotted releasing plate on said latch, a strap having a handle on its top edge whereby the strap is sustained in the well, the strap passing through the slot in the plate, and a stop on the strap for engaging 120 125 130

the releasing plate to limit the upward movement of the strap relative to the sash, and when so limited the sash acting to swing the latch to release it from the rack.

5 17. A window comprising a frame with a well, a sash adapted to be slid in and out of the well in a vertical direction, a strap in the well and slideable freely downward in its relation to the well and to the sash, and co-
10 acting means on the sash and the strap for

limiting the upward movement of the strap relative to the sash.

In testimony that I claim the foregoing, I have hereunto set my hand, this 28th day of April, 1914.

WILLIAM S. RAWSON.
